J. HORRIDGE

MACHINE FOR COMBING COTTON, WOOL, OR THE LIKE

Filed May 5, 1923

INVENTOR:
BY James Horridge
Mr Wallace White
ATTY.

UNITED STATES PATENT OFFICE.

JAMES HORRIDGE, OF BOLTON, ENGLAND, ASSIGNOR TO JOHN HETHERINGTON AND SONS LIMITED, OF MANCHESTER, ENGLAND.

MACHINE FOR COMBING COTTON, WOOL, OR THE LIKE.

Application filed May 5, 1923. Serial No. 636,820.

To all whom it may concern:

Be it known that I, JAMES HORRIDGE, a subject of the King of Great Britain, residing at Bolton, in the county of Lancaster, England, have invented new and useful Improvements in or Relating to Machines for Combing Cotton, Wool, or the like, of which the following is a specification.

The invention relates to improvements in machines for combing cotton, wool and the like and has for its object to provide adjustable means for mounting the stripping brush of a combing machine in such manner that said adjusting mechanism is easily accessible and at the same time to render the same capable of being readily dismantled in order to facilitate the substitution of new brushes.

The device is illustrated in the accompanying drawing wherein 1 represents the main frame of the machine, 2 represents the brush, which is of the usual type, 3 represents the cylinder shaft, 4 represents the nipper shaft and 5 represents a lever mounted with capability of oscillating or rocking upon a stud 6 or it might be a shaft extending the whole length of the machine, if desired, and at one end said lever 5 carries the brush shaft 7 upon which the brush 2 is mounted and at the other end it takes the form of a quadrant in which is provided a slot 8 through which projects a bolt 9 upon which screws a nut 10 which may be screwed up against the face of the lever 5 and so fix or clamp the same against movement.

The position of said lever 5 may, after the nut 10 has been loosened be adjusted by means of an adjusting screw 11 which passes through a threaded hole in an offset from the lever 5 and impinges upon the frame

1 of the machine, the nut 10 being afterwards tightened in order to fix the lever 5 in the position to which it has been adjusted.

By these means the adjusting mechanism 45 is easily accessible while it is simple to dismantle to allow of new brushes being fitted.

It will be understood that any suitable means may be employed to operate the adjusting mechanism above described, such 50 as a cam arranged rack and pinion or the like, and that the details of construction of the device may be modified without departing from the principle of the invention.

What I claim as my invention and desire to secure by Letters Patent is:—

1. In a machine for combing cotton, wool and the like, means for adjusting the stripping brushes comprising a pivoted rocking lever, said lever at one end carrying the brush shaft upon which the brushes are mounted, and at the other end provided with a slot, a bolt on the frame adapted to work in said slot, a nut adapted to screw on to 60 said bolt and bear against the face of the rocking lever, and an adjusting screw for adjusting said lever.

2. In a combing machine, the combination of a cylinder shaft, a lever pivoted intermediate its ends, a brush carried at one end of said lever in position to contact with said cylinder shaft, means for adjusting said lever thereby to carry the brush toward or away from the cylinder shaft, and 70 means for securing the lever in adjusted position.

In testimony whereof I have signed my name to this specification.

JAMES HORRIDGE.
